UNITED STATES PATENT OFFICE.

CHARLES R. BEALL, OF SWISSVALE, AND ROBERT M. GILSON, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA.

OVERLOAD-CIRCUIT BREAKER.

Application filed November 12, 1919. Serial No. 337,449.

To all whom it may concern:

Be it known that we, CHARLES R. BEALL and ROBERT M. GILSON, citizens of the United States, residing at Swissvale and 5 Pittsburgh, respectively, in the county of Allegheny and State of Pennsylvania, have invented certain new and useful Improvements in Overload-Circuit Breakers, of which the following is a specification.

10 Our invention relates to overload circuit breakers, and particularly to circuit breakers designed for operation by a prolonged current above a given value but not by a momentary surge of current above such value.

15 One object of our invention is the provision of a circuit breaker of this character which is simple and inexpensive to construct, yet reliable in operation.

We will describe two forms of circuit 20 breakers embodying our invention, and will then point out the novel features thereof in claims.

In the accompanying drawing, Fig. 1 is a 25 view showing one form of circuit breaker embodying our invention, and Fig. 2 is a view showing a modified form of circuit breaker also embodying our invention.

Similar reference characters refer to similar parts in each of the views.

30 Referring first to Fig. 1, the reference character 1 designates a core member having a pole-piece 1^a at the lower end. Attached to the upper end of this core is one leg of an L-shaped member 2 the other leg 35 of which is parallel to the core and terminates near the pole-piece 1^a. An armature 3 is pivotally attached to the lower end of the member 2 and is movable towards and away from the pole-piece 1^a. The parts thus far referred to are of magnetizable material, usually soft iron, and it will be seen that they constitute a magnetic circuit having an air gap which is maximum or minimum according as armature 3 is open or closed. This armature is biased to the open 45 position, and is, of course, closed when magnetic flux of sufficient density flows therethrough.

50 Mounted on the core 1 is a winding 4 for creating magnetic flux in the circuit just referred to. Between the winding and the core is a sleeve 5 of electroconductive material, such as copper, the purpose of which is to delay the building up of flux in the mag-

netic circuit during a sudden increase in 55 current strength in winding 4.

The magnetic circuit of the device is provided with a shunt magnetic path around the armature and air gap, this path being formed by a collar 6 of soft iron around the 60 core 1 between the pole-piece 1^a and the winding 4, which collar is spaced from member 2 by an air gap 7. In order to force a large proportion of the total flux through the shunt path during a momentary surge 65 of current in winding 4, a band 8 of electroconductive material is placed on the core 1 between the pole-piece 1^a and the collar 6. This band 8 and the sleeve 5, of course, have no effect on the flux created in the magnetic circuit by a current of constant value in winding 4.

The operation of the elements thus far referred to is as follows: As long as current of a definite value or less flows in winding 75 4 the armature 3 will remain open, but when a steady current of greater value is supplied to the winding the armature will close. When, however, the winding carries a momentary surge of current above such definite 80 value, the sleeve 5 will delay the building up of flux, and the band 8 will force the greater part of the increasing flux through the shunt path 6, 7, so that the flux density in armature 3 will be insufficient to cause 85 the latter to close. The surge of current will, therefore, have no effect on the device.

The circuit controlling portion of the device comprises a fixed contact member 9 and a contact spring 10 which normally tends to move away from member 9. Spring 10 is provided with a handle 12 by which it may be moved into engagement with the member 9, and it is normally held in the latter position by a latch 11. This latch is pivotally connected with the spring 10 at 11^a, and is provided with a shoulder 11^b which contacts with a hook 13 attached to a fixed block 14. When armature 3 closes, a toe 15 carried by the armature raises latch 11 and so 95 releases the latter from hook 13 so that the contact opens. It may be closed by means of handle 12. As here shown, the circuit breaker is included in circuit with a motor and a battery, the circuit being from battery 16, through motor 17, contact 19, winding 4, contact 9—10 to battery 16. The parts of the circuit breaker are so adjusted 100

that the normal operating current taken by motor 17 will not cause the breaker to open, but that a prolonged current above this value, such as will occur if the motor becomes stalled, will cause the breaker to open and so avoid injury to the apparatus. The current drawn by the motor while starting is, of course, in excess of the normal operating current, but this excess is merely a momentary surge which for reasons pointed out hereinbefore, has no effect on armature 3 and so does not cause the circuit breaker to open.

Referring now to Fig. 2, the breaker in the form here shown comprises, as before, a core 1 surrounded by a copper sleeve 5 and provided with a winding 4. Attached to the upper end of the core 1 is a U-shaped member 22 of magnetizable material, the two legs 22^a and 22^b of which are parallel to the core 1 and terminate adjacent the pole-piece 1^a. The armature, which is here designated 3^a, is pivotally mounted at 3^b in the pole-piece 1^a, the pivotal point being to the right of the middle point of the armature so that the armature is biased to the position shown wherein it is separated from leg 22^a by a block 20 of non-magnetizable material.

It will be seen that this structure provides two paths in multiple for the flux in core 1, one path being through leg 22^a and the right hand portion of armature 3^a, and the other path being through leg 22^b and the left hand section of the armature. When the armature is in the position shown, the air gap between the armature and leg 22^a is greater than that between the armature and leg 22^b, so that the reluctance of the right hand path is greater than that of the left hand path; consequently, when a steady current of a given value flows in winding 4 the armature will close, that is, it will swing in clockwise direction from the position shown. Leg 22^b is surrounded by a copper sleeve 21, so that most of the varying flux due to a momentary surge of current above the given value in winding 4 will be forced through leg 22^a and so will have no effect on armature 3. The building up of flux due to a surge of current is also delayed by a copper sleeve 5 as in Fig. 1. The operation of the device will be apparent from the foregoing explanation of the device shown in Fig. 1.

The control of contact 9—10 by the armature in Fig. 2 is the same as in Fig. 1.

Although we have herein shown and described only two forms of circuit breaker embodying our invention, it is understood that various changes and modifications may be made therein within the scope of the appended claims without departing from the spirit and scope of our invention.

Having thus described our invention, what we claim is:

1. An overload circuit breaker comprising

ing a magnet, a normally open armature associated therewith, a contact controlled by said armature; a magnetic shunt around said armature, and means for causing the greater part of the flux due to a varying current in said magnet to pass through said shunt; the parts being so proportioned that said armature closes on sustained current above a given value, but not on a momentary surge of current above such given value because of said shunt and the means for forcing varying flux therethrough.

2. A circuit breaker comprising a magnetic circuit having an air gap, and a member biased to a position wherein said air gap is maximum and movable to a position wherein said air gap is minimum, a winding for creating flux in said magnetic circuit, a branch path around said air gap, a band of electro-conductive material around a portion of said magnetic circuit for forcing the majority of a varying flux to pass through said branch path instead of through said air gap, and a contact controlled by said movable member.

3. A circuit breaker comprising a magnetic circuit having an air gap, and a member biased to a position wherein said air gap is maximum and movable to a position wherein said air gap is minimum, a winding for creating flux in said magnetic circuit, a branch path around said air gap, means associated with said magnetic circuit for forcing the majority of a varying flux to pass through said branch path instead of through said air gap, and a contact controlled by said armature.

4. A circuit breaker comprising a magnetic circuit having two paths in multiple, one of said paths including an air gap and a movable member biased to a position wherein said air gap is maximum and movable to a position wherein the air gap is minimum, a winding for creating flux in both of said paths, means for forcing the greater part of a varying magnetic flux through the other of said paths, a normally closed contact, and means for opening said contact when said member moves to its minimum air gap position.

5. A circuit breaker comprising a magnetic circuit having two paths in multiple, one of said paths including an air gap and a movable member biased to a position wherein said air gap is maximum and movable to a position wherein the air gap is minimum, a winding for creating flux in both of said paths, a band of electro-conductive material around a portion of said one path for forcing the majority of a varying flux through the other path, and a contact controlled by said movable member.

6. A circuit breaker comprising a magnetic circuit having two paths in multiple, one of said paths including an air gap and a

- movable member biased to a position wherein said air gap is maximum and movable to a position wherein the air gap is minimum, a winding for creating flux in both of said paths, means for forcing part of a varying magnetic flux through said other path, means for delaying the building up of magnetic flux in said circuit due to a current of increasing value in said winding, and a contact controlled by said movable member.
7. A circuit breaker comprising a magnetic circuit having an air gap and a movable member biased to a position wherein said air gap is maximum and movable to a position wherein the air gap is minimum, a winding for creating flux in said magnetic circuit, means for delaying the increase of flux in said magnetic circuit due to an increasing current in said winding, and a contact controlled by said movable member.
8. A circuit breaker comprising a magnet, an armature controlled thereby, a branch path of considerable reluctance for shunting part of the magnetic flux created by said magnet away from said armature, means for causing the greater part of a varying magnetic flux in said magnet to traverse said branch path, and a contact controlled by said armature.
9. A circuit breaker comprising a core, a winding thereon, a strap of magnetizable material extending from one end of said core to a location adjacent the other end, an armature pivotally attached to said strap and movable towards and away from the latter end of said core, a member of magnetizable material extending towards said strap from a point on said core at a point between said winding and the latter end of the core, a band of electroconductive material around the core between said point and the latter end of the core, and a contact controlled by said armature.
10. A circuit breaker comprising a magnetic circuit having two paths in multiple, one of said paths including an air gap and a movable member biased to a position wherein said air gap is maximum and movable to a position wherein the air gap is minimum, a winding for creating flux in both of said paths, means associated with said magnetic circuit for causing the greater part of a varying magnetic flux to pass through the other of said paths, a normally closed contact included in circuit with said winding, and means controlled by said movable member for opening said contact when the member moves to such position that the air gap is minimum.
11. A circuit breaker comprising a magnetic circuit having two paths in multiple, one of said paths including an air gap and a movable member biased to a position wherein said air gap is maximum and movable to a position wherein the air gap is minimum, a winding for creating flux in both of said paths, means associated with said magnetic circuit for causing the greater part of a varying magnetic flux to pass through the other of said paths, a contact biased to the open position, means for latching said contact in the closed position, and means for releasing said latching means when said movable member moves to the position wherein the air gap is minimum.
12. A circuit breaker comprising a fixed and a movable magnetic member, a winding on the fixed member, means for shunting away from the movable member part of the magnetic flux created in said fixed member by current in said winding, means for forcing a varying flux through said shunting means, and a contact controlled by said movable magnetic member.
- In testimony whereof we affix our signatures in presence of two witnesses.
